United States Patent Office

Des. 219,942
Patented Feb. 16, 1971

219,942

TIRE

John C. Smithkey, Jr., North Canton, and John R. Bauer and John H. Keck, Akron, Ohio, assignors to The Goodyear Tire & Rubber Company, Akron, Ohio, a corporation of Ohio

Filed Jan. 14, 1970, Ser. No. 20,927

Term of patent 14 years

Int. Cl. D12—14

U.S. Cl. D90—20

The figure is a perspective view of a tire showing our new design, it being understood that the design is repeated throughout the circumference of the tire, the opposite side being substantially the same as that shown.

We claim:

The ornamental design for a tire, substantially as shown and described.
